UNITED STATES PATENT OFFICE.

TYCHO VAN ALLER, OF SCHENECTADY, NEW YORK, ASSIGNOR TO GENERAL ELECTRIC COMPANY, A CORPORATION OF NEW YORK.

ELECTRIC HEATING UNIT.

971,101.

Specification of Letters Patent. Patented Sept. 27, 1910.

Application filed July 23, 1908. Serial No. 444,908.

To all whom it may concern:

Be it known that I, TYCHO VAN ALLER, a citizen of the United States, residing at Schenectady, county of Schenectady, State 5 of New York, have invented certain new and useful Improvements in Electric Heating Units, of which the following is a specification.

This invention relates to electric heating devices and has for its object the provision of an electric heating unit in which the heat is uniformly and evenly distributed in a simple and efficient manner.

One of the objects of my invention is to 15 provide a unit, which may readily be adapted for heating various shaped surfaces, and which may be applied to the part to be heated with a maximum of efficiency and simplicity.

20 In my previous application, Serial No. 432,023, I have described and claimed a unit which in a general way accomplishes the result above outlined. I have found, however, for many purposes that a unit which 25 is thinner than the one which I have described in said application is preferable.

In carrying out my invention I form a unit 30 of a resistance ribbon which is zig-zagged back and forth upon itself so as to form a continuous strip. This unit is preferably formed by winding the resistance conductor, which is covered with a thin film of insulation, into a closed helix and then flattening the helix upon itself. For this purpose I 35 have found a resistance conductor, which when heated is coated with an insulating oxid, very suitable, although a conductor insulated in any suitable manner may be used.

40 In the accompanying drawing, in which I have shown my invention embodied in concrete form, Figure 1 represents the outline of a flatiron with my flat unit applied thereto; Figs. 2, 3 and 4 represent the various 45 steps in the manufacture of the unit; Fig. 5 is an enlarged end view of the completed unit.

Referring to the drawing, 10 represents 50 my unit formed into a flat resistance ribbon. This unit is mounted upon a flatiron 11, preferably a short distance from the edge of the iron. I have found that by arranging this strip around the iron as shown that a 55 very satisfactory distribution of the heat is obtained. This distribution is particularly

effective when the flatiron is in service as the edges are chiefly active on the work and the short distance for the heat to travel easily maintains the temperature. This unit 10 consists of a ribbon 12, which is made by 60 first winding it around a core 13. The resistance ribbon may be of any suitable resistance material, preferably one which coats itself with an insulating oxid when heated. I have found that the wire disclosed in the 65 application of Dempster, No. 400,691, is suitable for this purpose. The ribbon which may be of any desired width is wound upon the core as shown in Fig. 2 and the core is then removed as shown in Fig. 3. The wire 70 may now be heated to form a coating of insulating oxid upon it by passing a current through it or it may be heated in any desired manner so as to produce this result. The manner of obtaining this insulating 75 coating upon the wire forms no part of my invention as any suitable insulation which is thin and will stand the heat may be used. After the spiral is made in the form shown in Fig. 3 it is flattened on itself until the 80 sides touch as shown in Fig. 4. This may be done by passing it through rollers or in any other desired manner. A resistance conductor is thus obtained which is substantially a wide resistance strip, but is of such 85 a nature that it may be bent into any desired shape. The extreme thinness of the unit makes it possible to be placed in very intimate thermal relation with the part to be heated and will occupy very little space. 90 The unit is produced at an extremely low cost and is very durable.

While I have described my invention in connection with a specific material which is oxidized by heat, it should be understood 95 that I do not limit my invention thereto except in so far as it is limited by the scope of the claims annexed hereto.

What I claim as new and desire to secure by Letters Patent of the United States, is,

1. A resistance unit comprising a helical conductor coated with a thin refractory insulation and flattened onto itself.

2. A resistance unit comprising a resistance ribbon wound into a helix and flattened 105 onto itself.

3. A resistance unit comprising a resistance ribbon wound into a closed helix and flattened onto itself.

4. A resistance unit comprising an insu- 110

- lated helical resistance ribbon flattened onto itself.
5. A resistance unit comprising an insulated resistance ribbon wound into a closed helix and flattened onto itself.
6. A resistance unit comprising a resistance ribbon wound into a helix and flattened onto itself and a terminal held within the helix by engagement therewith.
- 10 7. A resistance unit comprising a resistance ribbon wound into a helix and flattened onto itself and a flat terminal within the helix and engaged on opposite sides thereby.
- In witness whereof, I have hereunto set my hand this 21st day of July, 1908.

TYCHO VAN ALLER.
